US0D1069584S

(12) **United States Design Patent** (10) Patent No.: **US D1,069,584 S**
(45) Date of Patent: ** Apr. 8, 2025

(54) **BOTTLE FOR DISPOSER FLUID INJECTION ASSEMBLY**

(71) Applicant: **INSINKERATOR LLC**, Benton Harbor, MI (US)

(72) Inventors: **Sean E. Conaway**, Benton Harbor, MI (US); **Rico Taylor**, Benton Harbor, MI (US); **Nathan J. Wicker**, Rockville, MD (US); **Aaron B. Eiger**, Chicago, IL (US); **Mark F. Kurth**, La Porte, IN (US); **Peter P. Muller**, Chicago, IL (US)

(73) Assignee: **INSINKERATOR LLC**, Benton Harbor, MI (US)

(**) Term: **15 Years**

(21) Appl. No.: **29/883,426**

(22) Filed: **Jan. 27, 2023**

(51) LOC (15) Cl. **07-01**
(52) U.S. Cl.

USPC **D9/520**; D9/521; D9/575

(57) **CLAIM**

The ornamental design for a bottle for disposer fluid injection assembly, as shown and described.

DESCRIPTION

FIG. 1 is a front perspective view of the bottle for disposer fluid injection assembly;

FIG. 2 is a front elevational view of the bottle for disposer fluid injection assembly;

FIG. 3 is a rear elevational view of the bottle for disposer fluid injection assembly;

FIG. 4 is a right side elevational view of the bottle for disposer fluid injection assembly;

FIG. 5 is a left side elevational view of the bottle for disposer fluid injection assembly;

FIG. 6 is a bottom plan view of the bottle for disposer fluid injection assembly; and,

FIG. 7 is a top plan view of the bottle for disposer fluid injection assembly.

The broken lines illustrate environment and form no part of the claimed design.

1 Claim, 6 Drawing Sheets
